Fig. 2.

INVENTOR.

Margaret Beam.

UNITED STATES PATENT OFFICE.

MARGARET BEAM, OF BLOOMINGTON, ILLINOIS.

SANITARY TOILET PROTECTOR.

Application filed August 20, 1923. Serial No. 658,464.

To all whom it may concern:

Be it known that I, MARGARET BEAM, a citizen of the United States, residing at Bloomington, in the county of McLean and

State of Illinois, have invented a new, original, and useful Sanitary Toilet Protector, of which the following is a specification, reference being had to the accompanying drawing, forming part thereof.

10 The sanitary toilet protector is a necessity and benefit as a health protector in private homes, public buildings, hotels, railroad stations, and trains.

Referring to the drawing:

15 Figure 1 is the top plan view of the article spread out flat. 1 is the back, 2 is the front, 3 is a one-inch straight hem at the back, 4 a one-half inch hem receptacle for one yard of flat rubber for gathers, 5 is a one-inch bias facing on the oval opening. The principal dimensions are: 12 inches straight edge across the back with one-inch hem, 20 inches vertical diameter from back straight edge to front edge, 21½ inches horizontal diameter, 51 inches circumference from straight edge to straight edge, 4½ inches space from back straight edge to back edge of oval opening, 6 inches

from front edge of oval opening to front edge of circumference, 9½ inches vertical 30 diameter of the oval, 6½ inches horizontal diameter of the oval.

Figure 2 shows the under view of the sanitary toilet protector gathered with one yard of flat rubber. 1 is the back straight 35 edge, 2 is the front, 3 is the one-inch straight hem at the back, 4 is the one-half inch hem which contains one yard of elastic band for the purpose of drawing the edges of the cover under the seat and holding same in position 40 while in use. 5 is a one-inch bias facing on oval opening, centrally located, which conforms to the oval opening in the seat. All seams allowed.

I claim:

45 A sanitary toilet protector of washable rubberized cloth of substantially oval shape with a straight hemmed edge across the back, an oval-shaped opening therein, centrally located, a bias facing around same, a 50 hem around the circumference of said cover, an elastic band adapted to be contained therein for the purpose of drawing the edges of the cover under the seat and hold same in position while in use.

MARGARET BEAM.
